UNITED STATES PATENT OFFICE

2,413,710

SPRAYING APPARATUS

John P. Jason, Chicago, Ill., assignor, by mesne assignments, to Sprayer Corporation of America, Chicago, Ill., a corporation of Illinois

Application December 11, 1943, Serial No. 513,889

1 Claim. (Cl. 299—97)

1

This invention relates to novel improvements in the construction of a hand portable apparatus adapted to spray liquids such as insecticides, fumigants, deodorants and the like, by compressor action in the form of a fine mist.

In general the apparatus to which the improvements of the present invention relate comprises a unit composed of an encased motor, a separable liquid container and an intermediate compressor all axially arranged.

It is an object of the present invention to provide such apparatus in a more compact construction of reduced height. This is in part accomplished by providing a telescopic construction wherein the compressor extends within the liquid container. In addition to the advantage of reduction in height and the lowering of the center of gravity of the unit which makes it easier to handle and particularly gives it added security and stability when left standing alone on the container bottom for such uses as spraying or fumigating a room, the improved construction has the added advantage in that any oozings or leakage can run back into the liquid container instead of exteriorly thereof as was the case in former constructions.

Another object relates to the adjustable construction of the defining wall or sleeve of the compressor whereby it may be adjusted laterally to take up wear and provide the desired degree of eccentricity so as to enable the device to be operated with a maximum efficiency at all times.

Another object relates to the novel and improved form of spray nozzle with which my unit is provided whereby the direction of the issuing spray may be quickly and conveniently regulated by the provision of a rotatable head provided with a plurality of passages.

Another object relates to novel details of construction making provision for the picking up of oozings along the compressor shaft and for returning them to the compressor fluid intake.

Another object relates to the provision of float mechanism adapted to break the electrical circuit of the device to stop the operation thereof when the fluid in the container has been used up so as to avoid wear of the parts due to lack of lubrication by the fluid employed for spraying.

Other objects relate to added details of construction and arrangement of parts which will be apparent from a consideration of the following specification and drawings, wherein:

Fig. 1 is an elevation largely in central vertical section, with parts broken away, illustrating an improved sprayer unit in accordance with the present invention.

Fig. 2 is a section viewed on the line 2—2 of Fig. 1.

Fig. 3 is a section viewed on the line 3—3 of Fig. 1.

2

Fig. 4 is a longitudinal section of the novel spray nozzle.

Fig. 5 is a front elevation of a spray nozzle illustrated in Fig. 4.

Fig. 6 is a schematic wiring diagram for actuation and control of the unit.

Referring to the drawings, the reference numeral 10 generally indicates a motor enclosed in a dome-like casing 11, the open end of the casing being closed by the fitting generally indicated as 12 and secured thereto by means of screws as at 13. One end of the motor shaft 14 is journaled in the head of the casing 11 by means of the bearing 15, and the opposed end portion by means 15 of the bearing 16 in the fitting 12. The shaft 14 projects through the bearing 16 and has fixedly secured to its end portion the compressor rotor 17.

The fitting 12 is provided with a downwardly extending integral threaded annular flange 18, which is substantially an extension of the motor casing 11, and is adapted to threadably engage the complementary threaded neck 19 of the container 20. The body of the container is of relatively enlarged diameter and has a flat bottom so as to permit the unit as a whole to rest thereon.

The compressor comprises a rotor 17 provided with conventional vanes 21 slidably positioned in the rotor slots 22 and movable outwardly under centrifugal action, a separable side wall or sleeve 23 and the bottom cover or holder plate 29. The sleeve 23 which forms the rotor chamber is mounted in eccentric relation to the rotor 17 as is well understood in compressors of the type illustrated, but instead of being in fixed relationship as is conventional, I provide means for lateral adjustment of the sleeve 23 with respect to the rotor 17. This permits not only desired initial adjustment of degree of eccentricity and clearance of the two parts, but also permits adjustment to correct such desired eccentricity and clearance upon wear of the internal facing of the sleeve 23, with attendant increase in life of the compressor and the ability to conveniently maintain it at high efficiency at all times.

Such adjustability is accomplished by providing the sleeve 23 with a plurality of lateral ears 24 formed with apertures 25 to receive the screws 26 which extend into the fitting 12, the diameter of the apertures being larger than the diameters of the screws, as illustrated in Fig. 3 wherein one of the holding screws is removed. Thus, by loosening the screws 26, the sleeve 23 may be finely adjusted with respect to the rotor 17 and the screws thereafter tightened to securely hold the sleeve in desired position. The rotor chamber is completed and closed by the base plate 29 provided with a plurality of lateral ears 27 through which extend screws 28 into engagement with the fitting 12, the fitting 12 thus pro-

viding an end closure for both the motor casing and the compressor.

The fitting 12 is provided with a radial duct 30 which threadably engages the air inlet and liquid volume control nipple 31, the nipple being provided with a bore 32 extending longitudinally through it to permit introduction of a constant volume of air to the compressor through the air and liquid intake duct 33 which communicates with duct 30. The duct 30 is preferably formed with an intermediate annular seat 34 adjacent the orifice of the fluid introduction tube 35, which extends through the fitting 12 into communication with the duct 30, the said seat 34 providing an abutment for a complementary intermediate shouldered portion of the nipple 31 and whereby complete closure of the orifice of tube 35 is prevented, the nipple 31 being otherwise adjustable with respect to the orifice of tube 35 so as to enable regulation of the amount of liquid introduced into the compressor from the container 20. If desired a spring 36 may be seated within the duct 30 to bear against the reduced terminal end of the nipple 31, as illustrated, to prevent displacement of the predetermined adjustment of the nipple due to vibration of the unit in operation.

The fitting 12 is provided with a second radial duct 37 to which is threadably engaged the nozzle body 38 provided with the axial bore generally indicated as 39, the duct 37 communicating with the compressor through the air and vapor exhaust duct 40. The nozzle body 38 is provided with a spray tip 41, the tip being flanged as at 42 and held in rotatable engagement with the body 38 by means of the flanged nut 43 threadably engaged to the body 38. The bore 39 adjacent its outer end terminates in a plurality of branched conduits such as the axially offset parallel branch 39' and the 45° inclined branch 39''. The spray tip 41 is provided with holes 41' and 41'' adapted to register with the conduit branches 39' and 39'' respectively but not simultaneously. That is, when the openings 39' and 41' are aligned a horizontal spray is permitted to issue, but the openings 39'' and 41'' are at an angle of 120° from each other and out of communication. Conversely by rotating the tip 41 for 120° the openings 39'' and 41'' are brought into register to cause a spray to be emitted at an angle, with the openings 39' and 41' out of alignment and communication. Although only two sets of openings are shown in the illustration of Fig. 4, it will be understood that additional ports may be provided to individually register in the same manner. To aid in the prevention of leakage a gasket 44 may be interposed between the nozzle body and spray tip, suitably apertured for closing off openings so that only one passage of the nozzle is open at any one time. After the ports are set to spray at the selected angle they are held in position by tightening lock nut 43.

For the purpose of preventing oozing of liquid from the compressor upwardly along compressor-motor shaft 14 during operation of the device, I provide the bearing 16 with an annular groove 45 which is connected through the duct 46, which extends through the bearing 16 and fitting 12, to the duct 30, and thus permits any liquid which is forced upwardly along the shaft to be returned to the compressor through the air-liquid intake duct 33.

The unit is provided with a handle, generally indicated as 47 secured to the motor casing 11,

to permit the device to be operated while held in the hand, and when so held may be actuated by depression of the trigger switch 48 connected into the line 49. The spraying device is also conventionally employed by placing it on a suitable support such as a shelf or table within, for example, a room which is to be sprayed with insecticide, and for such purpose a conventional timer switch mechanism, such as that described in United States Patent No. 1,990,165, and generally indicated as 50 is provided in handle 47, and connected in line 49 in parallel with trigger switch 48. By setting the timer switch the sprayer may be actuated for a predetermined length of time, within the limits of the mechanism, without requiring the presence of the operator.

However, when the device is set for operation by means of the time switch 50 the possibility always exists that the liquid in container 20 will become exhausted before the switch 50 opens, due either to a too high rate of flow of the fluid or too long a time setting in proportion to the amount of liquid in the container, and in the absence of the operator, continued actuation of the device after exhaustion of the liquid will cause undue wear of the compressor parts due to lack of lubrication by the liquid. In order to prevent such occurrence I provide the container 20 with a float 51, the rod 52 of which extends and reciprocates through a suitable aperture in the fitting 12 to terminate within the motor casing 11 adjacent the contiguous portion of the handle 47 and the timer switch 50 thereof. The upper end of rod 52, between its setting stop 53 and its breaker stop 54, extends freely through the end of a lever 55 pivoted at 56, for actuation of the micro switch, diagrammatically indicated as 57, and connected in series with the time switch 50. It will be understood that, although not illustrated, switch 57 may in the alternative be a mercury or merccid switch actuated by tilting of the lever 55. Thus, when the container 20 is filled with liquid, stop 54 on float rod 52 rises to tilt lever 55 to a position where it closes switch 57, and if the timer switch 50 is also closed by setting for a predetermined period of operation, the device will continue to operate until either switch 50 opens at the end of its set time or until the liquid in the container has reached a level where the rod 52 has become lowered to an extent where its stop 53 depresses lever 55 sufficiently to open switch 57, whichever occurs first, and thus actuation of the sprayer device and wear of the compressor parts prevented in the absence of sufficient liquid in the container, when the device is operated by means of the timer switch.

I claim as my invention:

60 A hand portable, compact, unitary liquid spraying device of the class described comprising a liquid container having a threaded top opening, a partitioning member threaded onto said threaded opening in said container to provide a cover therefor, said partitioning member having a flat bearing surface formed on its bottom side, an encased motor mounted upon said partitioning member, a rotor driven by said motor and having its upper side bearing against said flat bearing surface, and a sleeve surrounding said rotor and adjustably engaging the flat bearing surface of said partitioning member for radial adjustment with respect to said rotor.

JOHN P. JASON.
